END-LASTING MECHANISM.

1,306,247.

Specification of Letters Patent.

Patented June 10, 1919.

Application filed September 14, 1915. Serial No. 50,629.

To all whom it may concern:

Be it known that I, MATTHIAS BROCK, a citizen of the United States, residing at Boston, in the county of Suffolk and State of 5 Massachusetts, have invented certain Improvements in End-Lasting Mechanisms, of which the following description, in connection with the accompanying drawings, is a specification, like reference characters on the 10 drawings indicating like parts in the several figures.

This invention relates to shoe shaping machines and is herein embodied in an end lasting mechanism.

15 The more recent developments in the shapes of lasts and the corresponding shapes of shoes have, similarly to the gradual development during the past twenty years, been in the direction of approximating the 20 shape of the last to the shape of the human foot so that the present day last is more nearly like the human foot than lasts ever before used.

This type of last is now in general use and 25 is characterized by unsymmetrical shapes on the two sides of the heel and also on the two sides of the toe. In the case of the heel, generally speaking, the lasts are characterized by extreme fullness on the outer side of the 30 heel extending through the shank, the inner side of the heel extending into the shank being correspondingly "cut away." This results in an unsymmetrical relation of the tread face of the last at the heel end to the 35 counter portion above it.

Under these conditions, it is highly desirable that the end clamping means of a lasting mechanism be arranged to conform to these opposite side faces of the last. In a 40 form of heel lasting mechanism in wide use and shown in United States Letters Patent No. 1,018,477, granted September 12, 1911, upon my prior application, and in connection with which the present invention is shown, 45 the heel seat wipers and heel band are mounted for bodily transverse swinging adjustment together relative to a toe support and about a center located approximately at the intersection of the longitudinal median lines 50 of the forepart and heel part of the supported last to position the wipers in symmetrical

relation to the tread face of the last at the heel seat. No provision is made, however, for adjustment of the heel clamping band to position the band to conform to the opposed 55 full and cutaway side faces of the heel end of the last since the heel band and wipers move together in symmetrical relation.

An important feature of the present invention consists in an end clamping means,— 60 as shown, an end embracing band,—, and supports for the ends of said band and a support for the embraced end of the shoe arranged for preliminary relative bodily adjustment transversely relative to the shoe 65 support and shoe to position the clamping means to conform to, or in symmetrical relation to the opposite full and cut away side faces of the end of the last. When the mechanism of the present invention is applied to a lasting machine of the type shown and described in the patent previously referred to and to which the band adjusting mechanism is adapted, bodily adjustment of the end embracing band is effected independently of the bodily transverse swinging adjustment of the wipers and band, and enables the band to be positioned in unsymmetrical 70 relation to the tread face of the end of the last when lasts of the described type are to 75 be operated upon.

As shown, means for supporting the ends and the middle rear portion of the end clamping band are carried by a yoke which is manually adjustable transversely of the 85 machine and of a supported last to adapt the band for uniform clamping action against the opposed full and cut away sides of right and left lasts preliminary to the closing of the band. The described adjustment may 90 also be utilized, when needed, for manually applying special or extra pressure against a side of the heel end or shank portion of the upper at or near the end portions of the heel stiffener after the band has been closed in 95 order to shape the heel stiffener and upper to the deep concavity at the inner side of the last. By this means, the shoe materials may be positively forced firmly against the side of this portion of either a right or left 100 last.

A further feature of the invention con-

sists in novel means for obtaining shaping pressure against the shoe upper at the "corners," or rounded portions located between the rear end and the sides, of the heel 5 end of the shoe and last. As shown, a stiff spring is arranged to exert pressure against each corner of the heel as the shoe is forced into position to be operated upon. These springs are carried by the yoke previously referred to and in the ordinary adjustment of the yoke are effective substantially to equalize the pressure on the two corners of the heel. In another adjustment of the yoke the springs, which act through the 15 usual heel embracing band and its supporting chain, may be caused to effect greater pressure on one corner than on the other of a particular shoe.

A further feature of the invention consists in a novel heel band support. This is shown as comprising articulated elements constructed and arranged to apply properly proportioned degrees of pressure to the upper and the lower portions of a heel band 25 for forcing the upper materials against the last along the lower as well as the upper part of the band.

The several features of the invention, including certain details of construction and 30 more important combinations of parts, will be more fully understood from the following description of the illustrated embodiment of the invention and will then be pointed out in the claims.

35 Figure 1 of the drawings is a plan view of a portion of a heel lasting mechanism in which this invention is embodied.

Fig. 2 is a perspective view of the corner pressure applying means and the side pressure applying means.

40 Fig. 3 is a perspective view showing novel band supporting means.

The illustrated mechanism is a heel lasting head and includes a part 2, which may be 45 regarded as a frame, relatively to which a last carrier 3 provided with a heel pin 4 is movable by pinion 6 and band wheel 5 to force a shoe into position to be operated upon. The frame has supporting bearings 50 in which a yoke-shaped member 8 is mounted, said member having guide slots 10 cooperating with guide studs in the frame to direct movement of the yoke transversely of the frame. The yoke supports the front 55 end portions of bar 12 which operate levers 14 connected at their inner ends with the ends of a heel band chain 15 and having their outer ends connected by relief springs 16 to the frame 2. The rear ends of bars 12 60 are connected through a cross-head 18 with a plunger 20. Forward movement of the plunger is transmitted to the band chain to tension the band ends forwardly. The bars 12 have wedge or incline faces 13 which 65 coöperate with abutments 9 fixed on the

yoke 8 to force the bars, levers and band chain ends inwardly at the same time that the band ends are tensioned forwardly. The band chain is supported at its middle by a stud which enters a hole 7 in the yoke and 70 is secured by a binding screw. These parts are, in the respects described, substantially like the construction shown in United States Letters Patent No. 1,018,477, granted Sept. 12, 1911 on my prior application. 75

The yoke 8 supports two like springs 25, each of which has a long vertical arm, a neck, a short vertical arm and a horizontal attaching portion which is adjustably held by a binding screw 26 in a downward extension 27 of the yoke 8. These springs are located to bear against the heel band chain and apply a stiff pressure at the corners of the heel when the shoe is jacked back into the heel band by the hand wheel 5 from the 80 dotted line position shown in Fig. 1. The shape and mounting of the springs 25 gives them capacity for adaptation without substantial change of pressure to wide differences in the size of heels. 90

The yoke 8, instead of being free to slide transversely of frame 2 as in my prior patent, has threaded engagement with a screw 30 which can rotate without advancing in the frame 2 and the screw has a large head 95 by which it can be turned to move the yoke transversely of the machine in the direction of slots 10 bodily to move the chain and heel band transversely to position to conform to the full outer and cut away inner 100 sides of the last, the springs 25 acting under these conditions to equalize pressure on the two corners of an unsymmetrically shaped heel part of a last. Under certain conditions the described adjustment means may 105 also be used to apply through springs 25 extra or special pressure to one corner or other of the heel.

The described means for moving the yoke 8 constitutes provision for applying pressure, through an abutment 9, a bar 12, a lever 14 and an end portion of the heel band, to the side of a shoe. This arrangement may be employed as a means for manually applying special or extra pressure 110 when needed against the heel end or shank of the upper at and near the end portions of the heel stiffener to shape the heel stiffener and upper to the deep concavity at the inner side of the last after the band 115 has been closed and ordinarily will be used at a right and left adjustment to position the band and its operating mechanism so that when the bars 12 are advanced with their wedges in contact with abutments 9 a substantially equal pressure will be applied at the cutaway inner side of a last and at the fuller outer side of that last. 120

The heel band supporting chain carries 125 pressure equalizing members 35 which are 130

- pivoted upon the chain between their upper and lower ends and extend from the top edge of the band nearly to its bottom edge. The inner band engaging face of each pressure equalizing member 35 is contoured vertically to fit the portion of the side face of the heel part of the last to which it is opposed. The member 35 which is shown at the left in Fig. 3 is contoured to fit the forward portion of the heel. The members which are opposed to the rear end of the heel are differently contoured to fit the smaller degree of vertical curvature which is formed on the end of the heel. The chain 15 is shown as constructed, for the purpose of properly carrying said pressure equalizing members, of pairs of link members 36 between which are interposed the heads of other link members 38, connected thereto by vertical pivot pins 39. The link members 38 are formed with necks 40 which constitute horizontal pivots on which the pressure equalizing members 35 are mounted for independent pressure equalizing movement. The described construction serves the purpose of applying suitably proportioned pressure through the lower and the upper portions of the band to clamp the upper materials, including the heel stiffener, firmly 25 against the side faces of the last from its bottom edge downwardly for substantially the full width of the heel band, which is usually in excess of the width of the heel stiffener. A heel band made in accordance with this invention molds the heel stiffener and the upper to the last throughout the width of the stiffener, whereas heel bands have usually firmly engaged only the portion of the upper at and adjacent to the 30 shoe bottom.
- Having explained the nature of this invention and described an illustrative embodiment of it, I claim as new and desire to secure by Letters Patent of the United States:—
1. An end lasting mechanism having, in combination, means for clamping a shoe upper to the sides of its last, and springs independent of said clamping means and arranged with relation to the upper clamping means to force the upper materials of the shoe at the corners of the heel hard against the last.
  2. An end lasting mechanism having, in combination, means for supporting a shoe on its last, springs arranged with relation to the supporting means to force the upper materials of the shoe at the corners of the heel hard against the last, said springs having a long vertical arm, a bend, a short vertical arm and a horizontal attaching arm, and means for supporting each spring for independent adjustment in the direction of the length of the attaching arm.
  3. An end lasting mechanism having, in combination, means for clamping a shoe upper to the sides of its last, springs independent of said clamping means and arranged with relation to said clamping means to force the upper materials of the shoe at 70 the corners of the heel hard against the last, and operating means for effecting relative movement of the shoe and the springs to apply pressure of the springs against the upper materials.
  4. An end lasting mechanism having, in combination, a heel embracing band, means to cause the band to close upon and conform the heel end of a shoe upper to the heel end of a last, and springs independent 80 of said band closing means and arranged to exert pressure against the band at the opposite corners of the heel end of the last.
  5. An end lasting mechanism having, in combination, a heel embracing band, springs 85 arranged to engage the band opposite to the corners of the heel and hold the engaged portions of the band in positions to require the band to be spread to admit the heel end of the shoe, means for forcing the shoe into 90 the band and means to cause the band to embrace and conform the heel end of a shoe upper to its last.
  6. An end lasting mechanism having, in combination, a heel embracing band, a band 95 chain, a support for the rear end of the band chain, and springs carried by said support and arranged to press inwardly the portions of the band engaging the corners of the heel.
  7. An end lasting mechanism having, in combination, means for supporting a shoe on its last, a yoke movable transversely of the shoe, a heel embracing band carried by the yoke and springs also carried by said 105 transversely movable yoke and arranged to effect pressure against the corners of the heel embraced by the band.
  8. An end lasting mechanism having, in combination, means for supporting a shoe 110 on its last, springs arranged with relation to the supporting means to force the upper materials of the shoe at the corners of the heel hard against the last, and means to effect adjustment to increase the pressure of 115 a spring against the shoe while the shoe is in the lasting mechanism.
  9. An end lasting mechanism having, in combination, means for supporting a shoe on its last, springs arranged with relation 120 to the supporting means to force the upper materials of the shoe at the corners of the heel hard against the last, and means adapted to effect and retain preliminary adjustment of the two corner springs simultaneously to adapt them for right and left shapes of lasts.
  10. An end lasting mechanism having, in combination, means for supporting a shoe on its last, two springs arranged respectively 125

- to apply pressure at the corners of the heel of the shoe, and means for adjusting the springs together transversely of the shoe.
11. An end lasting mechanism having, in combination, means for supporting a shoe on its last, a heel embracing band, and two bar springs the upper ends of which are free and project into position to apply inward pressure through the heel band to the corners of the heel of the shoe.
12. An end lasting mechanism having, in combination, means for supporting a shoe on its last, a heel embracing band, two bar springs the upper ends of which are free and project into position to apply inward pressure through the heel band to the corners of the heel of the shoe, a support for the springs and a screw for adjusting the support transversely of the shoe.
13. A heel lasting mechanism having, in combination, a heel embracing band, means for tensioning the band forwardly, means for closing the band, said closing means including a member which is mounted for right line movement transversely of the machine, and an adjuster for effecting movement of said member and holding it in adjusted position.
14. In a lasting machine, the combination with a heel band, of slide bars connected with the end portions of the band, inclines on said slide bars, abutments coöperating with the inclines to force the slide bars and band ends inwardly as the bars are advanced, and means for effecting and maintaining adjustment of the abutments transversely of the machine.
15. In a lasting machine, the combination with a heel band, of slide bars connected with the end portions of the band, inclines on said slide bars, abutments coöperating with the inclines to force the slide bars and band ends inwardly as the bars are advanced, and means to adjust a slide bar in the direction of the movement thereof effected by the coöperation of an abutment and the incline on said bar, and to maintain such adjustment.
16. An end lasting mechanism having, in combination, a shoe support, an end embracing band, supports for the ends of the band, and means for effecting coincidently bodily adjustment of said supports in the same transverse direction relatively to the shoe support.
17. An end lasting mechanism having, in combination, a support for one end of a shoe, a band arranged to embrace said end of the shoe, means for supporting the free front ends of the band, and means for effecting and maintaining bodily adjustment of the supporting means for the two ends of the band simultaneously relatively to the shoe support and in a direction transverse relatively to the shoe support.
18. An end lasting mechanism having, in combination, a support for one end of a shoe, a band arranged to embrace said end of the shoe, means for supporting the middle rear portion of the band and for supporting the front ends of the band, and means arranged for manual operation for effecting adjustment of said supporting means relatively to the shoe support and in a direction transverse relatively to the shoe support.
19. An end lasting mechanism having, in combination, a shoe support, an end embracing band, means for supporting the band, a frame on which the band supporting means is bodily movable transversely of the shoe support, and a screw threaded into the band supporting means and rotating without end-wise movement in the frame and provided with a head constructed and arranged for convenient operation by the workman bodily to adjust the band transversely of a shoe on the shoe support.
20. An end lasting mechanism having, in combination, a shoe support, an end embracing band, means for supporting the band ends, means for closing the band, and a screw having an operating head constructed and arranged for convenient operation by the workman to increase the closing pressure effected through an end of the band after a shoe is embraced by the band.
21. An end lasting mechanism having, in combination, a shoe support, an end embracing band, means for supporting the band ends, means for closing the band, and a screw operatively connected with the two band ends for manipulation to effect a preliminary adjustment of the band ends transversely of the machine and relatively to the shoe support to adapt the band for a right or a left last.
22. An end lasting mechanism having, in combination, a heel embracing band, a band chain, and pressure equalizing members connected to the chain by horizontal pivots and having inner faces which extend from the top substantially to the bottom of the band and are contoured to conform substantially to the vertical curvature of the portion of the side face of the last to which they are opposed.
23. An end lasting mechanism having, in combination, a heel embracing band, a band chain, and pressure equalizing members arranged in a series around the band and independently movable about horizontal pivotal connections with the chain.
24. An end lasting mechanism having, in combination, a heel embracing band, a band chain, and pressure equalizing members arranged in a series around the band and each contoured on its inner face to conform substantially to the vertical contour of the portion of the side face of the last to which it is opposite.

25. An end lasting mechanism having, in combination, a heel embracing band, a band chain comprising links presenting horizontal pivot members, and pressure equalizing members mounted on said pivot members and engaging the band above and below said pivot members. 70
26. An end lasting mechanism having, in combination, a heel embracing band, means for closing the band, a pressure member at each end of the band formed to apply pressure at the upper and lower parts of the band and mounted to turn about a horizontal pivot, and a screw by which relatively variable pressures can be applied through said members to opposite ends of the band. 75
27. An end lasting mechanism having, in combination, an end clamping band to embrace and conform a shoe upper to the sides of one end of its last, means for closing said band to force the upper into conformity to the last, and relatively stiff spring means independent of said closing means and arranged with relation to said clamping means to exert substantial pressure against said clamping means to transmit additional pressure to the clamped upper materials at the corners of the heel. 80
28. An end lasting mechanism having, in combination, end embracing means for clamping and conforming one end of a shoe upper to the sides of its last, means for closing said embracing means to force the upper into conformity to the last, and means independent of said closing means and arranged with relation to said clamping means to exert substantial pressure against said clamping means to effect additional clamping pressure against the upper materials at the corners of the heel for substantially the full width of the counter. 85
29. An end lasting mechanism having, in combination, an end embracing band, means for tensioning the band forwardly, means for closing the band positively to force the shoe materials against the sides of an end portion of the last, and manually adjustable means determinately to control closing pressure of the band against opposite sides of the last end. 90
30. A heel lasting mechanism having, in combination, a heel embracing band, means for tensioning said band forwardly, means for closing said band to conform the shoe upper materials to the heel end of the last and means independent of the band closing means for determinately controlling the inward pressure of the opposite sides of the band against the upper materials at the opposite sides of the heel end of the last. 95
31. An end lasting mechanism having, in combination, an end embracing band, means for tensioning the band forwardly, means for closing the band to conform the shoe upper materials to the end of the last and means independent of the band closing means for determinately varying the relative inward pressure of the opposite sides of the band against the upper materials at the opposite sides of said end of the last. 100
32. An end lasting mechanism having, in combination, an end embracing band, and means acting against the ends of the band to tension the band forwardly and to close the band to conform the shoe upper materials to the end of the last, the said band and its tensioning and closing means being supported and arranged for bodily adjustment prior to the closing of the band to position the ends of the band to conform to full and cut away faces of the last at opposite sides of the end of the last. 105
33. An end lasting mechanism having, in combination, a support for one end of a shoe, a band arranged to embrace said end of the shoe, a support for the ends of said band, means for closing the band to clamp the upper materials to the sides of one end of the last, and means for effecting a preliminary bodily adjustment of the band support relatively to said shoe support and in a direction transversely of a supported shoe to position the band to conform to the opposed full and cut away side faces of a last end. 110
34. An end lasting mechanism having, in combination, a support for the heel end of the shoe, a heel end embracing band, means for supporting the ends and middle rear portion of the band, manually operable means for effecting preliminary bodily adjustment of the band supporting means relatively to said shoe support and in a direction transverse relatively to a supported shoe to position the band at an angle to the tread face of the shoe for conformation to the cut away face at one side and the full face at the opposite side of the heel end of the last, and means for closing the band to clamp the upper materials to the sides of the heel end of the last. 115
35. An end lasting mechanism having, in combination, a support for one end of a shoe, a band arranged to embrace said end of the shoe, a support for the ends and middle rear portion of the band, band closing means mounted on said support, and manually operable means for effecting bodily adjustment of said band support, band, and closing means relatively to said shoe support and in a direction transverse relatively to the shoe to position the band at an angle to the tread face of a supported shoe prior to operation of the band closing means. 120
36. An end lasting mechanism having, in combination, a support for the heel end of the shoe, a heel embracing band, supports for the ends of said band, means to close the band to clamp the upper materials to the side faces of the last end, and means manually operable bodily and determinately to 125

adjust the band end supports relatively to said heel support in a direction transverse relatively to a supported shoe.

37. An end lasting mechanism having, in combination, a support for one end of a shoe, a band arranged to embrace said end of the shoe, a support for the ends of the band, a base on which said band support is mounted for relative movement, manually operable means for bodily adjusting said band support on said base and relatively to said shoe support in a direction transversely of a supported shoe and last determinately to position the ends of the band relatively to the full and receding surfaces of the opposite side faces of the last end prior to the closing of the band, and means for closing the band.

38. An end lasting mechanism having, in combination, a support for one end of a shoe, a band arranged to embrace said end of the shoe, a support for the middle portion of the band, members acting against opposite sides of the band, and means for coincidentally adjusting said band support, band and said members relatively to said shoe support and in a direction transversely of a supported shoe.

39. An end lasting mechanism having, in combination, a support for the heel end of a shoe, a heel embracing band, a support for the middle rear portion of the band, pressure

members acting against opposite sides of the band approximately at the corners of the heel end of a supported shoe, and means for coincidentally adjusting said band support, pressure members and band relatively to said shoe support and in a direction transversely of a supported shoe.

40. An end lasting mechanism having, in combination, a support for one end of a shoe, a band arranged to embrace said end of the shoe, a support for the middle portion of the band, members acting against opposite sides of the band between its ends and middle portion, a common carrier for said band support and said members, and means for adjusting said carrier with the band support, band and said members relatively to said shoe support and in a direction transversely of a supported shoe.

41. An end lasting mechanism having, in combination, a heel embracing band, means for closing the band, a pressure member at each end of the band formed to apply pressure at the upper and lower parts of the band and mounted to turn about a horizontal pivot, and manually adjustable means by which additional pressure can be applied through one of said members.

In testimony whereof I have signed my name to this specification.

MATTHIAS BROCK.
